PLATE-PRINTING DEVICE

Albert G. Wahl, Los Angeles, Calif.

Application June 15, 1938, Serial No. 213,774

5 Claims. (Cl. 101—269)

My invention relates generally to printing or stamping devices and, more particularly to a device adapted to be used by sales people in retail establishments for printing the names, addresses, and other identifying indicia upon sales slips and the like that are issued by the sales people to the customers at the time a sale of goods is made and which procedure in addition to identifying the customer as a person entitled to credit and having a charge account at the establishment using printing devices, is effective in materially reducing the time ordinarily required in completing a sales transaction between sales people and persons entitled to credit and who are furnished with metal plates embossed with their names and other identifying indicia.

The principal objects of my invention are, to generally improve upon and simplify the construction of the existing forms of plate printing or stamping devices, to provide a device that does not require the use of an inked ribbon for producing the impression upon the sales slip or the like and further, to provide a printing device of the character referred to that is compact, strong, and durable in construction and which may be conveniently manipulated to effect the printing operations on the sales slips that are generally assembled in book form or carried between folding covers.

30 A further object of my invention is, to provide a printing device wherein the embossed metal plates that carry the customer's names and other identifying indicia are detachably positioned on a solid base and the device including a manually operable frame mounted for swinging movement above the embossed plate and said frame carrying at its lower end a roller of compressible material which, as the frame swings backward and forward, rolls across the embossed plate so as to effect the printing of the inserted sales slip.

With the foregoing and other objects in view, my invention consists in certain novel features of construction and arrangement of parts that will be hereinafter more fully described and claimed and illustrated in the accompanying drawing in which:

Fig. 1 is a perspective view of a plate printing device constructed in accordance with my invention.

50 Fig. 2 is a vertical longitudinal section taken on the line 2—2 of Fig. 1.

Fig. 3 is a cross section taken on the line 3—3 of Fig. 2.

Fig. 4 is a horizontal section taken on the line 55 4—4 of Fig. 2.

Fig. 5 is a horizontal section taken on the line 5—5 of Fig. 3.

Fig. 6 is a plan view of one of the embossed plates used in the plate printing device.

Fig. 7 is a longitudinal section taken on the 5 line 7—7 of Fig. 6.

Fig. 8 is a longitudinal section through the center of a modified form of the impression roller.

Referring by numerals to the accompanying 10 drawing which illustrates a preferred embodiment of my invention, 10 designates a base plate preferably formed of metal and which may be of any desired size and shape and secured on top of said base plate is a secondary base 11, preferably rectangular in form and somewhat smaller in dimensions than the main body plate 10. Connected by a hinge 12 to the upper rear edge of base 11 is the rear edge of a horizontally disposed rectangular frame 13, preferably formed of metal, 20 and which includes side rails 14 that are substantially L-shape in cross section so as to provide inwardly presented flanges 15. Formed integral with or fixed to the corners of the frame 13 are the lower ends of the vertical legs of inverted U-shaped frames 16 and applied to said frames and enclosing the same and also enclosing the frame 13 is a housing 17, preferably constructed from thin sheet material.

For the reception of the identifying embossed 30 plates, the central portion of the upper face of base 11 is provided with a shallow recess 18, preferably rectangular in form and the marginal portions of this recess on all four sides are increased slightly in depth to form a continuous 35 groove or channel 19. At the front end of recess 18, a depression 20 is extended forwardly a short distance in order to provide a pocket that receives the end of the finger that is utilized in tilting the embossed name plate when the same 40 is removed from the base.

The name plates 21 as illustrated in Figs. 6 and 7 are preferably formed of sheet metal with their marginal edges bent downwardly and inwardly to form beads 22 which, when the plates 45 are positioned in the recess 18, occupy the marginal groove or channel 19. Each plate is embossed with upwardly projecting characters that form the name, address, and other identifying indicia for the customer to whom the plate is 50 issued, such characters being in reversed arrangement after the manner of the characters on conventional printing type, so that when the printing of a sales slip is effected the characters appear in proper and readable arrangement 55

thereupon. If desired, a slip of heavy paper or card such as 23 may be applied to the under side of the printing plate and retained in position thereon by the inwardly turned flanges that form 5 the beads 22 as illustrated in Fig. 7 and this slip or card may bear the written signature and other identifying data of the person to whom the plate is issued.

Seated in the upper portions of the frames 16 10 directly above the center of the recess 18 are the ends of a transversely disposed rod 24 and mounted for swinging and sliding movement thereupon is a plate-like frame 25.

The upper portion of this frame is provided 15 with slots 26 for the accommodation of rod 24 and thus the plate is permitted to move lengthwise during its backward swinging movement upon said rod.

The lower portion of the swinging frame 25 20 is notched as designated by 27 for the accommodation of an impression roller 28, which latter is formed of compressible material, preferably rubber or composition having rubber as one of its ingredients and said impression roller is carried 25 on a transversely disposed shaft 29, the ends of which bear directly upon the upper surfaces of the flanges 15 of the side rails 14.

Projecting from the ends of the shaft 29 are 30 trunnions 30 that are journaled in the lower end of the swinging frame 25 to the sides of the notch 27 therein. The front side of swinging frame 25 above the notch 27 is recessed for the accommodation of expansive coil springs 31, the lower portions of which are disposed about pins 35 32 that project upwardly from that portion of the frame immediately below the recess and immediately above the notch 27 and the upper ends of said springs bear against the ends of a plate 33 that is mounted for rocking movement 40 on the central portion of rod 24.

These springs 31 yieldingly resist the upward movement of the swinging frame as the lower end thereof and the roller carried thereby moves lengthwise of the printing plate positioned in recess 18 on base 11.

Secured to the lower portion of the swinging frame 25 adjacent the lower ends of the springs 31 are the ends of retractile springs 34, the opposite ends of which are secured to the upper 50 portion of the adjacent end rail of frame 13. Thus said springs 34 normally maintain the frame 25 at the forward end of its travel as illustrated by solid lines in Fig. 2 and said springs yieldingly resist the rearward swinging movement of 55 said frame.

Mounted for swinging movement on a transversely disposed rod 35, the ends of which are seated in the front portions of the inverted U-shaped frames 16, is a substantially L-shaped 60 hand lever 36, one arm of which extends through an opening 37 formed in the upper front portion of housing 17 and from said opening the lever extends upwardly and forwardly to provide a convenient handle 38 that is grasped and swung 65 downward to operate the printing device. The short arm of the hand lever extends downwardly a short distance within the housing 17 and pivotally connecting the end of this arm of the lever with the intermediate portion of swinging frame 70 25 is a link 39.

In the use of my improved plate printing device, the sales person after receiving the embossed name plate from the customer and making 75 out the sales slip covering the transaction, raises the hinged upper portion of the device by swing-

ing same upwardly and rearwardly on the hinge 12 and then inserts the name plate in the recess 18. A piece of carbon paper is now laid over the name plate with the carbon surface uppermost and the sales slip is now positioned over the carbon paper. The upper hinged portion of the device is now moved downward until it rests on base 28 and the handle 38 is now forced downward with pressure. As the hand lever moves 5 on its fulcrum 35, the link 39 swings the frame 10 25 on its fulcrum (the rod 24) so that the impression roller 28 carried by the lower end of the frame rides over the sales slip and carbon paper positioned directly over the name plate 15 with the result that the letters on the name plate are through the carbon paper printed on the sales slip.

As frame 25 swings rearwardly in the machine 20 it moves a short distance upward, which movement is permitted by the slots 26 through which 20 rod 24 passes, and this rearward swinging movement of the frame is yieldingly resisted by the retractile springs 34. After the frame has thus been moved to its rearward limit of movement as illustrated by dotted lines in Fig. 2, pressure upon 25 the hand lever is relieved and the power stored in the springs 34 act to return the frame to its normal position and during this forward swinging movement of the frame, the impression roller 28 passes the second time over the printing plate 30 and the carbon paper and sales slip positioned thereupon, thus insuring a clear and defined printing of the embossed letters onto the sales slip.

During the swinging movement of frame 25 and 35 the travel of the roller 28 over the printing plate, said roller is under pressure of the expansive springs 31.

After the printing operation as just described 40 has been effected, the hinged upper portion of the device is swung upwardly and rearwardly and after the sales slip and carbon paper have been removed, the embossed plate is removed from recess 18 and returned to the customer.

To facilitate removal of the printing plate from 45 the base, the pressure of the finger upon the end of the plate adjacent the recess 20 will tilt said plate so that it may be readily grasped and withdrawn from recess 18.

In Fig. 3 I have shown a modified form of the 50 impression roller and which modified construction comprises a cylindrical body 40, which may be formed of wood, metal, hard rubber, or composition, and carried on the periphery thereof is a layer 41 of fibrous material, preferably felt. In 55 applying the felt, I prefer to coat the periphery with a suitable adhesive; for instance, an elastic paint, and then to blow thereonto felt fibers which adhere to the cylinder and which provide a flexible and to a certain extent elastic surface for 60 the roller.

Obviously, rollers of this construction may be 65 used in machines other than plate printing machines.

Thus it will be seen that I have provided a 70 plate printing device that is relatively simple in construction, inexpensive of manufacture, and very effective in performing the functions for which it is intended.

It will be understood that minor changes in the size, form and construction of the various parts of my improved plate printing device, may be made and substituted for those herein shown and described, without departing from the spirit of 75

my invention, the scope of which is set forth in the appended claims.

I claim as my invention:

5. 1. In a plate printing device, a base adapted to support a printing plate, a frame hinged to said base, a second frame mounted for swinging and sliding movement within said first mentioned frame, a substantially bell crank shaped handle fulcrumed in the upper portion of said hinged frame in front of said second mentioned frame, the short arm of which bell crank handle extends downwardly from its fulcrum point, a link connecting the short arm of said bell crank handle with the intermediate portion of said swinging and sliding frame and a roller journaled for rotation in fixed bearings on the lower portion of said swinging and sliding frame for engaging the face of the printing plate positioned upon said base.
10. 2. A plate printing device as set forth in claim 1, with means associated with said swinging and sliding frame for yieldingly resisting its sliding movement in one direction and for causing the roller to engage the printing plate with yielding pressure.
15. 3. A plate printing device as set forth in claim 1, with means for yieldingly resisting the sliding movement of the sliding and swinging frame in one direction and for applying yielding pressure to said roller and separate means for yieldingly

resisting the swinging movement of said swinging and sliding frame in one direction.

4. In a plate printing device, a base provided in its upper portion with a recess for the reception of an embossed printing plate, a frame hinged to said base, a second one piece frame arranged within said first mentioned frame, a pivotal and sliding connection between the upper portion of the second mentioned frame and the upper portion of the hinged frame, an impression roller journaled in the lower portion of said second mentioned frame and adapted to pass over the printing plate supported on the base, means arranged between the two frames for yieldingly resisting the upward sliding movement of the second mentioned frame, a substantially bell crank shaped handle pivotally mounted in the upper portion of said hinged frame, that portion of the handle within the frame extending downwardly from the pivot point of said handle and a link pivotally connecting the end of the downwardly extending portion of the handle to the intermediate portion of said second mentioned frame.

5. A plate printing device as set forth in claim 4 and with means connecting the front portion of the hinged frame with the lower portion of the swinging frame for yieldingly resisting rearward movement of said swinging frame.

ALBERT G. WAHL. 30
